WELT COATING MACHINE

Arthur Bates and John Henry Brown, Leicester,
England, assignors to United Shoe Machinery
Corporation, Paterson, N. J., a corporation of
New Jersey

Application November 10, 1932, Serial No. 642,072
In Great Britain December 1, 1931

26 Claims. (Cl. 91—50)

This invention relates to machines for preparing welting strips for use in the manufacture of welt shoes and more particularly to a machine for coating that portion of a strip of welting which is to receive the inseam stitching, which unites the welting to the shoe upper and insole, with a sealing substance which will aid in waterproofing the shoe along the inseam and at the region adjacent to the inseam. It is to be understood, however, that in many of its novel aspects the invention is not limited merely to treating welting strips for use in producing shoes with sealed inseams, but may be used for coating various other articles and materials such, for example, as fabrics or rubber.

In the manufacture of certain types of welt shoes the welting strip is prepared by beveling its inner edge and by grooving its flesh surface and sometimes also its grain surface, adjacent to the beveled edge, to receive the row of stitching which is to unite the welting to the shoe upper and insole. When the welt is attached to the shoe, this line of stitching or inseam passes through the stitch-anchoring groove in the flesh side of the welt and through the groove in its grain surface, which lies next to the upper, if that surface is grooved, thus permanently securing the welt to the upper and insole. In order to insure that the shoe will be water-tight along the inseam after the welt is attached, it has been proposed in United States Letters Patent No. 1,937,826, granted December 5, 1933, on an application filed in the name of R. A. Linehan for improvements in the Manufacture of shoes, to coat the welting strip with a sealing substance which will fill the groove formed on the side of the welt which lies next to the upper and will cover a portion of the welt adjacent to this groove, thereby sealing the inseam stitches and aiding in rendering the shoe waterproof.

It is an object of the present invention to provide an improved machine whereby the coating of welting strips with a sealing substance can be effected rapidly, accurately, and with facility. To the attainment of this object and in accordance with a feature of the invention, the illustrated machine is provided with novel means for applying a coating substance to a welting strip, said means comprising a rotary applying member which is arranged to deposit the coating substance downwardly on the welting strip as the strip is fed transversely of the periphery of the rotary applying member from side to side thereof. In the construction shown the rotary member is mounted on a horizontal axis located

substantially parallel to the path of feeding movement of the welting strip and the strip is fed lengthwise across the applying surface of the rotary member, scraping the coating substance from the latter and depositing it on a marginal portion of the welting strip during the feeding movement.

Another feature of the invention resides in novel means for supporting the welting strip with one of its sides in contact with the periphery of the rotary member during the rotation thereof, and for holding this side of the strip in contact with the periphery of the rotary member during the feeding movement. Preferably, and as illustrated, this is accomplished by means of a thrust member which presses the strip toward the firm-surfaced periphery of the rotary applying member, the thrust member being slidably mounted in a guideway formed in the frame of the machine and having a tongue for supporting the portion of the strip in contact with the rotary member against the downward thrust of said rotary member. Means is provided in the illustrated machine for urging the thrust member inwardly toward the rotary member, thus keeping the welting strip in proper contacting relation to the periphery of the rotary member as the strip is fed through the machine.

Other features of the invention reside in novel means for limiting the area of the surface of the welting strip which is to be coated, and means for controlling the quantity of coating material deposited on the strip. As illustrated, the limiting means comprises a gage member which bears against a portion of the length of the welting strip during its feeding movement and acts as a fence to limit the area widthwise of the strip which receives the coating substance. The means for controlling the quantity of coating material applied to the welting strip comprises a controlling gage in the form of a block, located in the path of feeding movement of the welting strip between the rotary member and the feeding means, and arranged to bear lightly against a portion of the upper surface of the welting strip as it is fed through the machine to scrape off or hold back the surplus. The controlling gage or block may, if desired, be provided with a groove to permit the passage of a bead of coating substance which extends above the surface of the welt.

The invention also includes as further features novel means for adjusting the controlling gage and for withdrawing it from engagement with the welting strip, and means for retracting the

width gage and the thrust member simultaneously in order to permit the introduction of a welting strip to the operating instrumentalities. In the construction shown, the means for withdrawing the gages consists of manually operable members which are so located that an operator may operate and control them with one hand thus leaving the other hand free to insert a welting strip into the machine.

10 The above and other features of the invention, including certain details of construction and combinations of parts, will now be more particularly described by reference to the accompanying drawings and thereafter pointed out in the claims.

15 In the drawings,

Fig. 1 is a front elevation partly in section of the upper portion of the machine in which the present invention is embodied;

20 Fig. 2 is a plan view of the machine shown in Fig. 1 with the top cover removed;

Fig. 3 is an elevation of the welt strip feeding mechanism as viewed from the rear in Fig. 1;

Fig. 4 is a vertical section through the feed rolls; and

25 Fig. 5 is a cross section on enlarged scale of a strip of welting after the coating substance has been applied.

The illustrated machine comprises a base 12 the upper portion of which forms a reservoir 14 which contains the coating substance that is to be applied to the welting strip. A coating substance or wax which may advantageously be used for coating strips of welting or other articles of this nature is disclosed in the above-mentioned application and contains asphalt, Chatterton's compound and resin. The invention is not limited to the use of such substance, however, but is intended to include any substance of this general nature which can be applied to strips of welting 30 or similar materials for the purposes herein set forth. The under side of the reservoir 14 may be heated in order to melt the coating substance and keep it in liquid form until it is applied to the welt. Heat may be applied to the reservoir 35 by any suitable means such, for example, as a gas burner illustrated at 16 or an electric heating unit (not shown) which may be introduced in a recess 18 formed under the reservoir for this purpose. The top of the reservoir is provided 40 with a removable lid or cover 17 which retains the heat in the reservoir.

The coating substance is applied to the welting strip from the periphery of a firm-surfaced rotary applying roll 20 and is supplied to the applying roll by means of a supply roll 22, the lower portion of which dips into the coating substance contained in the bottom of the reservoir. The supply roll 22 is rotatably mounted on the lower arm of a bell crank lever 24, pivoted on a stud 26 mounted in ears formed in the lower portion of the reservoir. The other arm of the bell crank lever 24 extends upwardly and is threaded at its upper end to receive a screw 25 which passes outside the reservoir through an opening and has mounted on its outer portion a spring 27. The inner end of the spring 27 bears against a washer mounted on the screw 25 and bearing against the outer wall of the reservoir and the other end of the spring presses against an enlarged head 28 of the screw and tends normally to force the screw outwardly, thus causing the supply roll 22 to be urged upwardly into peripheral engagement with the applying roll 20.

The applying roll 20 is secured to a horizontal shaft 32 rotatably mounted in bearings formed

on the side walls of the reservoir. The shaft 32 is rotated through spiral gears 34, 36 by a driving shaft 38 journaled in bearings formed outside the reservoir and extending laterally of the machine and at right angles to the shaft 32. The driving shaft 38 has a handle 40 by which it may be rotated when the machine is in operation. The applying roll 20 is rotated in a clockwise direction, as viewed in Fig. 1, so that the coating substance deposited on its periphery by the supply roll 22 will be carried over the top of the roll and deposited downwardly or piled upon a marginal portion of the upper or grain surface of a welt strip 44 (Fig. 1) as the latter is being fed across the periphery of the roll in a manner hereinafter 10 to be described.

The thickness of the film of coating substance on the applying roll 20 may be controlled by a scraper plate 90 adjustably secured to a lug formed inside the reservoir. The scraper plate 20 90 may be provided with grooves 92 (Fig. 2) for controlling the amount of coating substance carried by the applying roll and, if desired, the peripheries of the supply roll and applying roll may also be provided with grooves (not shown) in order to increase the quantities of coating material carried by the rolls.

Progressive feeding of the welting strip is effected by a pair of cooperating feed members comprising a feed wheel 42 and a presser roll 46. 30 The feed wheel 42 is mounted on the drive shaft 38 and is substantially equal in width to the widest welting material which is to be coated. The periphery of the feed wheel is obliquely grooved or ribbed (Fig. 3), so that the welting 35 strip 44 will be held from slipping as it is fed over the top of the wheel. The grooves are so inclined that the welting strip will be urged laterally toward the applying roll as it passes over the periphery of the feed wheel. The presser roll 46 is rotatably mounted in a forked carrier 48, directly above the feed wheel 42, and is adapted to press the welting strip 44 firmly against the feed wheel during the welt feeding operation. The periphery of the presser roll 46 is 45 provided with horizontal grooves which cooperate with the oblique grooves in the feed wheel 42 to prevent the welting from slipping as it is fed through the machine. The carrier 48 for the presser roll 46 is mounted in a bracket 50 fixed 50 to the reservoir 14 and a spring 52 (Fig. 3) tends normally to force the presser roll downwardly into engagement with the feed wheel. The presser roll 46 is considerably narrower than the feed wheel 42 and is so located with respect to the feed 55 wheel that it will press upon a portion of the welting strip which is not to be coated. Since the axes of the feed wheel 42 and the applying roll 20 are at right angles to each other, the welting strip 44 is fed laterally across the periphery of the applying roll in a path which is parallel to the axis of said applying roll and perpendicular to the axis of the feed wheel. The presser roll 46 may be separated from the feed wheel 42, to permit a welting strip to be inserted 60 between them and to this end there is provided a lever 54 pivotally mounted at 56 on the bracket 50 and connected by a screw 57 to the carrier 48. When it is desired to introduce a welting strip into the machine the lever 54 may be rotated about 70 its pivot 56 by means of a small latching hand lever 58 to lift the presser roll 46 and hold it away from the feed wheel, thereby providing space to insert the end of the welting strip between the feed members.

When a melted coating substance of the nature referred to is used, it has been found that a satisfactory coating may be applied to a strip of welting by utilizing an applying roll about three-eighths of an inch wide and by feeding the welting past the applying roll at a speed equal to the peripheral speed of the applying roll. In the construction shown this may be attained by employing a feed wheel 42 of half the diameter of the applying roll 20 and by arranging the spiral gearing 34, 36, through which the applying roll is rotated, so that the applying roll shaft 32 will be rotated at half the speed of the feed wheel 42. A convenient diameter for the applying roll under these circumstances is about two and three-quarter inches.

In order that the welting strip 44 may be supported in the desired relation to the applying roll 20, as it is fed through the machine, there is provided a device for holding the strip against the periphery of the applying roll with the surface which is to receive the coating substance uppermost. This device comprises a thrust member 62 (Fig. 1) mounted for sliding movement toward and away from the applying member in a horizontal slot 63 (Fig. 2) formed in a supporting portion 60 projecting from the side of the reservoir adjacent to the feed rolls 42, 46. The thrust member 62 has a strip supporting tongue 64. This slot is located opposite the periphery of the applying roll 20 and the upper surface of the tongue 64 is substantially aligned horizontally with the top of the feed wheel 42, in a plane substantially parallel to the axis of the applying roll 20 and intersecting its periphery. At its inner end the guideway opens into a horizontal guideway having a side surface 63a parallel to that element of the periphery of the roll 20 which contacts with the edge of the welt-40 ing and, as shown, is parallel to the axis of the applying roll. The guideway also has a bottom surface 63b (Fig. 4) in a plane intersecting the surface of the applying roll. This guideway 63a, 63b extends transversely of the applying roll and in it is supported the welting strip as it is fed through the machine. The top of the tongue 64 (Fig. 4) is level with the bottom 63b of the guideway and together they support the welting strip. The edge face 44a (Fig. 5) of the welting strip 50 adjacent to the sewing groove 65 (and to the coating groove 67 if the latter is present) is kept in close contact with the periphery of the applying roll 20 by the thrust member 62, which is pressed inwardly toward the periphery of the applying roll at right angles to the path of feeding movement of the welting strip by a leaf spring 68. The thrust member 62, adjacent to the tongue 64 (Fig. 1) which supports the welting strip directly in front of the applying roll, has a vertical surface 66, for engaging the edge face 44b of the welt opposite that which contacts with the applying roll, thereby to press the welting strip against the periphery of the applying roll to scrape off the coating substance and to deposit it on the margin of the top or broad face 44c of the welting strip, filling the groove 67 if there is such a groove. This grooved-upper face or grain side of the welt will be next to the upper and the coating substance will seal the inseam 60 stitch and aid in rendering the shoe waterproof. The leaf-spring 68, which urges the thrust member 62 toward the periphery of the applying roll, is mounted on a projection 69 formed at the lower portion of the reservoir.

In order to limit the area widthwise of the

welting strip to which coating substance will be applied or can spread, there is provided a width gage 70 comprising a fence-like plate pivoted at 72 to the support 60 and having a portion of its lower edge bearing against the upper surface of the welting strip (Figs. 1 and 4). The width gage 70 is positioned parallel to the length of the welting strip as the latter is fed through the machine and is pressed downwardly by means of a leaf-spring 74 (Fig. 2) secured to an upper portion of the support 60 and bearing against the top edge of the gage plate. The gage 70 is thus caused to press against a length of the welting strip for a predetermined distance either side of the location where the welting strip passes the periphery of the applying roll 20.

The thickness of the coating applied to the welting strip is determined by a controlling gage in the form of a block 76 pinned on the inner end of a horizontal rod 78 pivotally mounted in the supporting portion 60 of the reservoir. The block or gage 76 extends over that portion of the welting strip which has been coated and acts to scrape excessive material from the surface, thereby controlling the thickness of the layer of coating substance applied to this surface. The controlling gage is located (as shown in Fig. 2) at a point in the path of feeding movement of the welting strip that is behind the applying roll 20 and in front of the feed wheel and presser 30 roll. The gage is spring pressed about its pivot 78 so that it will bear downwardly upon the upper surface of the welting strip as the latter is fed through the machine. The under side of the controlling gage 76 may be grooved as at 77 (Fig. 35), when so desired, to permit the passage of a bead 79 of coating substance which extends above the surface of the welting as shown in Fig. 5 directly over the filled groove 67.

The gages 70, 76 are each provided with manually operable means by which they may be lifted when a welting strip is being introduced into the machine, such as a knob 80 secured to the forward end of the gage 70, and a forwardly extending lever 82 the rear end of which is secured to the rod 78 which forms the pivot for the controlling gage 76. The lever 82 may be swung upwardly by an operator to rotate the rod 78 and lift the gage 76 away from the welting, downward movement of the lever to position the gage and control the thickness of the coating substance, being limited by an adjustable screw 84 threaded through an overturned portion of the lever and arranged to engage the upper surface of the support 60. The upper edge of the width gage 70 is beveled at a portion of its length which lies in front of the applying roll 20. A slide plate 86, adjustably secured to the thrust member 62 and arranged to slide in a groove formed in a cover plate 88 mounted on the support 60, has its forward edge, which is contiguous to the gage 70, beveled so that it is complementary to the bevel on the edge of the width gage. When the width gage is raised to permit a welting strip to be inserted underneath it, these beveled surfaces come into engagement with each other and the thrust member 62 is forced back against the spring 68, thereby creating sufficient space between the applying roll 20 and the vertical surface 66 of the thrust member 62 to permit the welting strip to be inserted therebetween.

In the operation of the machine the gages 70, 76 are first lifted by the manually controlled members 80, 82 and a welting strip 44 or other

piece of work is inserted in the guideway 63a, 63b formed in the supporting portion 60. The drive shaft 38 is then rotated by the handle 40 to actuate the feed wheel 42 and, through the 5 gearing 34, 36, to rotate the shaft 32 and the applying roll 20. The supply roll 22, which is rotated by frictional engagement with the applying roll 20, is caused to pick up coating substance from the reservoir 14 and deposit a layer 10 on the periphery of the applying roll. The applying roll then deposits the coating substance downwardly on the margin of the broad upper surface 44c of the welting strip 44, as the latter is fed laterally across its periphery by the feed 15 wheel 42 and presser roll 46. The welting strip is held in proper relation to the periphery of the applying roll by the action of the thrust member 62, which forces the narrow edge face 44a of the strip adjacent to the roll in close 20 contact with the periphery of the roll thereby to scrape off the melted wax. The under side of the strip directly in front of the applying roll is supported during the feeding movement by the tongue 64 which extends forwardly to within a 25 short distance of the periphery of the roll. The width gage 70 limits the area of the coating substance applied widthwise of the welting strip and, as the coated surface of the strip is fed past the controlling gage 76, the acting edge 30 of the gage scrapes off the excessive coating material, thereby determining the thickness of the layer of coating substance remaining on the broad upper face 44c of the welting strip.

Having thus described our invention, what we 35 claim as new and desire to secure by Letters Patent of the United States is:—

1. A machine for coating a strip of welting having, in combination, applying means for piling a coating substance on a strip of welting, 40 means arranged to feed the strip laterally past the applying means, a width gage for preventing the spread of the coating substance widthwise of the strip, and a scraper for controlling the quantity of coating substance to be left on the strip.

2. A machine for coating a strip of welting having, in combination, a relatively narrow rotary member for applying a coating substance to a strip of welting, means for feeding the strip transversely of the narrow face of said 50 rotary member, and a member having a guideway for said strip including movable means bearing against one edge for holding an opposite edge surface of the welting in contact with said applying surface during said feeding movement thereby to scrape coating substance from the rotary member on to an adjacent surface of the 55 welting.

3. A machine for coating a strip of welting having, in combination, an applying roll, the work-contacting portion of which moves downwardly and is arranged to deposit a coating substance on a strip of welting, means for feeding the welting strip from side to side of the periphery of the applying roll, and movable means for thrusting the strip laterally into scraping contact with the periphery of the applying roll thereby causing the strip to receive coating substance on the adjacent upper surface, said 60 thrusting means having an underlying tongue for supporting the portion of the strip which is in contact with the roll against the downward thrust of the roll.

4. A machine for coating a strip of welting 75 having, in combination, a rotary member for

applying a coating substance to a strip of welting, means for feeding said strip laterally across the periphery of said rotary member, and means spaced from the applying member and bearing against the strip along a line parallel to the path of feeding movement for limiting the area of the welting material to which coating substance is applied. 5

5. In a machine for coating a strip of welting, a rotary applying member, means for supplying a coating substance to said member, means for feeding a welting strip from side to side of the periphery of said rotary member with an edge surface of the welting in substantially contacting relation to said periphery whereby the coating 10 substance is scraped from the applying member and deposited upon an adjacent surface of the welting, and a plate-like fence the edge of which extends in the direction of movement of the strip and rests thereupon to protect a portion 15 of said adjacent surface of the welting from the spread of the coating substance. 20

6. A machine for coating welting having, in combination, a rotary member for applying coating substance to the welting, means for feeding 25 the welting lengthwise across the periphery of said member, movable means to thrust one edge surface against said periphery to scrape off coating substance and pile it up upon an adjacent surface, a relatively stationary plate-like gage 30 bearing on a portion of said adjacent surface and extending in the direction of the feeding movement for limiting the width of the coated strip, and means to exert pressure laterally on the thrust member and downwardly on the gage. 35

7. A machine for coating a strip of welting having, in combination, a rotary member for applying a coating substance to a welting strip, means for feeding the strip edgewise past the periphery of the rotary member in a path extending substantially at right angles to the plane of rotation of said rotary member, means for causing rotation of said rotary member in a direction that will scrape off coating substance and deposit it downwardly on the upper surface of 45 the welting strip, a gage for limiting the spread of coating material deposited on the strip, said gage being arranged to contact with the welting strip for a predetermined distance either side of the periphery of said rotary member, and means 50 for holding the gage in contact with said welting strip.

8. A machine for coating a strip of welting having, in combination, a rotary member for applying a coating substance to a strip of welting, 55 means for feeding the strip lengthwise across the periphery of said rotary member, means for holding the strip in contact with said periphery during the feeding movement, a device for confining the spread of the coating substance to a limited 60 area of the welting strip, said device being arranged to bear against the strip in a direction parallel to the path of feeding movement, and resilient means for holding said device against the welting strip. 65

9. In a machine for coating a strip of welting, a rotary applying member, means for supplying a coating substance to said member, means for feeding a welting strip from side to side of the periphery of said rotary member with an edge 70 of the welting in substantially contacting relation to said periphery whereby the coating substance is scraped from the applying member and deposited upon an adjacent surface of the welting, and means acting upon the coating applied 75

to said adjacent surface for controlling the thickness thereof as the welting is fed past said controlling means.

10. A machine for coating a strip of welting having, in combination, an applying roll for depositing a coating substance on a strip of welting, means for feeding the strip horizontally across the width of said applying roll, a width gage for limiting the area widthwise of the welting strip to which coating substance is applied, and a scraper for controlling the quantity of coating substance remaining on the welting strip.

11. A machine for coating a strip of welting having, in combination, a rotary member for applying a coating substance to a strip of welting, means for feeding the strip from side to side across the periphery of said rotary member, and a gage for controlling the thickness of the coating applied to said welting strip, said gage having 20 a groove formed in its acting surface to permit the formation of a bead of coating substance which extends above the surface of the welting strip.

12. A machine for coating a strip of welting having, in combination, a rotary member for applying a layer of coating substance to a strip of welting, feed rolls for feeding the welting strip from side to side across the periphery of said rotary member, a gage for controlling the thickness of the layer of coating substance on the welting strip, and means for varying the position of said gage relatively to the welting strip.

13. A machine for coating a strip of welting having, in combination, a rotary member for applying a layer of coating substance to a strip of welting, a pair of rolls for feeding the welting strip horizontally across the periphery of the rotary member in a path lying substantially in the plane of the axis of said member, means for supporting the welting strip edgewise relatively to said periphery during the feeding movement, means for applying pressure to an edge of the strip remote from the edge adjacent to the periphery of the rotary member to keep said adjacent edge in contact with said periphery during said feeding movement, and a scraper for controlling the thickness of the coating applied to said welting strip as it is fed past said scraper.

14. A machine for coating a strip of welting having, in combination, a rotary member for applying a coating substance to a strip of welting, means for feeding the welting strip from side to side across the periphery of said rotary member with the surface to receive the coating substance uppermost, means for limiting the area widthwise of said surface upon which coating substance is applied, and a scraper for removing excessive coating substance from said surface.

15. A machine for coating a strip of welting having, in combination, a rotary member for applying a coating substance to a strip of welting, a pair of feed rolls for feeding the welting strip laterally across the applying surface of said rotary member, a presser to hold the strip edgewise against the applying member, means for causing separation of the feed rolls to permit the welting strip to be inserted therebetween, and means for retracting said presser.

16. A machine for coating a strip of welting having, in combination, a rotary member for applying a coating substance to a strip of welting, a pair of rolls for feeding the welting strip, said rolls being mounted on axes extending at right angles to the axis of the rotary member, means for guiding the welting strip laterally

across the periphery of said rotary member constructed and arranged to press against one edge of the strip to force the opposite edge into engagement with the periphery of said rotary member, and means for retracting said guiding means to permit introduction of the welting strip between the rotary member and the guiding means.

17. A machine for coating a strip of welting having, in combination, a rotary member for applying a coating substance to a strip of welting, means for feeding the welting strip from side to side across the periphery of said rotary member with one edge face contacting with said periphery, means for pressing said edge face against the periphery of said rotary member, a width gage for limiting the area of the strip laterally to which coating substance is applied, and single means for simultaneously retracting the pressing means and the width gage, to facilitate introduction of the welting strip into the machine.

18. A machine for coating a strip of welting having, in combination, a rotary member for applying the coating substance to a strip of welting, means for feeding the welting strip from side to side across the periphery of said rotary member, a presser member for causing an edge of the welting strip to wipe against said periphery during such rotation, thereby scraping from said periphery a quantity of coating substance which is deposited on the surface of the strip adjacent to said wiping edge, a width gage for limiting the spread of the substance widthwise of the strip, and a scraper limiting the quantity of coating substance left on the strip.

19. A machine for coating a strip of welting having, in combination, a reservoir for holding a coating substance, a rotary member for applying the coating substance to a strip of welting, a pair of rolls for feeding the strip edgewise across the periphery of said rotary member, slideable means for guiding the strip during its feeding movement, resilient means acting on said guiding means to press the edge of the strip into contact with said periphery, and gages to limit the width and thickness of the coating substance left on the strip.

20. A machine for coating a strip of welting having, in combination, a member rotatable on a horizontal axis for applying a coating substance to a strip of welting, means for feeding the strip in a horizontal path that crosses the periphery of the rotary member substantially in the plane of the axis of said rotary member, means for pressing an edge of the welting strip against said periphery during the feeding movement, and resilient means, bearing lengthwise on the strip, for limiting the width of the coating substance applied to said welting strip.

21. A machine for coating a strip of welting having, in combination, a reservoir containing a coating substance, a rotary member for applying the coating substance to a strip of welting, means for feeding the strip from side to side across the periphery of the rotary member, a roll for transferring coating substance from the reservoir to the periphery of said rotary member, a fence for limiting the spread of the coating substance on a surface of the welting strip, and a gage for controlling the quantity of coating substance applied to said strip, said gage being provided with a groove to permit the formation of a bead of coating substance which extends above the surface of the welting strip.

22. In a machine for applying a coating to articles having opposite broad faces connected by an edge surface, a rotatable applying member,

a work support having a movable member constructed and arranged to press the work laterally in a direction substantially parallel to a broad face thereby to force the edge surface of an article against the periphery of the applying member, and means for moving the article longitudinally of the axis of rotation.

23. In a machine for applying a coating to the margin of one surface of a piece of work, said work having a face to be coated and an opposite face connected thereto by an edge surface, a rotatable applying member having its operative peripheral portion moving downwardly, means having a surface lying in a plane intersecting the periphery of the applying member for supporting said work adjacent to the applying member, means for thrusting said work laterally transversely of the work supporting surface to press the edge surface of the work against the applying member to cause the latter to pile an excess of coating material upon the adjacent upper margin, limiting means for determining the quantity and position of the coating material left upon the margin, and means for feeding said work in a direction substantially parallel to the axis of rotation of the applying member.

24. In a machine for coating along its margin one face of a strip of welting adjacent to an edge thereof as the welting travels lengthwise, a rotatable coating-applying roll contacting with the edge of the welting, a member having a welting-supporting surface lying in a plane intersecting the periphery of the roll, means for supporting the roll with its periphery substantially out of contact with the face to be coated, means for rotating the roll in a direction to cause its coating-

applying periphery to move in the general direction of and then past the face to be coated, and means tending to move the welting transversely to its line of travel and toward the periphery of said roll thereby holding one edge against said roll and scraping the material therefrom on to the face of said welting not contacting with said roll.

25. In a machine for coating a strip of welting having broad upper and lower faces connected by narrow edges, a rotatably mounted, driven coating-applying roll, the periphery of which, as it rotates, moves toward and then past the edge of the face of the welting which is to be coated, means having a surface for supporting said welting and lying in a plane intersecting the periphery of the roll, said means tending to hold the edge of the welting in contact with the roll to scrape the coating material therefrom on to the surface of the welting not in contact with said roll, and means for feeding the welting strip in a path parallel to that element of the periphery of the roll which is in contact with the edge of the welting.

26. A machine for coating a strip of welting having, in combination, a rotatable roll for applying a coating substance to a strip of welting, means for feeding the welting longitudinally, and means for supporting the strip and holding it pressed transversely to the line of travel with one edge against the applying roll to scrape the material therefrom on to the face of the welting not in contact with said applying roll.
